DESIGN FOR A PISTOL-GRIP SCREW DRIVER

Joseph M. Cashmore, Chicago, Ill., assignor to Montgomery Ward & Co., Incorporated, Chicago, Ill., a corporation of Illinois

Application January 14, 1937, Serial No. 67,064

Term of patent 14 years

To all whom it may concern:

Be it known that I, Joseph M. Cashmore, a citizen of the United States, residing at Chicago, in the county of Cook and State of Illinois, have invented a new, original, and ornamental Design for a Pistol-Grip Screw Driver, of which the following is a specification, reference being had to the accompanying drawing, forming a part thereof.

In the drawing,

Fig. 1 is a side elevation of a pistol-grip screw driver showing my new design;

Fig. 2 is an edge elevation thereof; and

Fig. 3 is an end elevation of the screw driver.

I claim:

The ornamental design for a pistol-grip screw driver, as shown.
